US00D440641S

(12) **United States Design Patent** (10) **Patent No.:** **US D440,641 S**
Hollinshead et al. (45) **Date of Patent:** **** Apr. 17, 2001**

(54) **FLEXIBLE SHOWER ARM**

(75) Inventors: **Milton B. Hollinshead; Robert B. Male**, both of Fort Collins, CO (US); **Andrew Serbinski**, Annandale, NJ (US)

(73) Assignee: **Water Pik, Inc.**, Newport Beach, CA (US)

(**) Term: **14 Years**

(21) Appl. No.: **29/064,772**

(22) Filed: **Jan. 10, 1997**

(51) LOC (7) Cl. **23-03**

(52) U.S. Cl. **D23/304**

(58) Field of Search **D23/283, 303, D23/304, 264-266; 4/596, 567, 570, 605, 615; 239/587.1, 588**

Assistant Examiner—Eric Watterson

(74) Attorney, Agent, or Firm—Dorsey & Whitney LLP

(57) **CLAIM**

The ornamental design for a flexible shower arm, as shown and described.

DESCRIPTION

FIG. 1 is a front perspective view of a flexible shower arm showing our new design;

FIG. 2 is a side elevational view, the opposite side being a mirror image thereof;

FIG. 3 is a top plan view thereof;

FIG. 4 is a bottom plan view thereof; and,

FIG. 5 is a front plan view showing an alternative position thereof.
